UNITED STATES PATENT OFFICE.

ALEXANDER CLASSEN, OF AACHEN, GERMANY.

PROCESS FOR THE MANUFACTURE OF NITRIC ACID OR NITRATES FROM NITROGEN OXIDS.

1,178,440.

Specification of Letters Patent.

Patented Apr. 4, 1916.

No Drawing.

Application filed February 14, 1916. Serial No. 78,5

To all whom it may concern:

Be it known that I, ALEXANDER CLASSEN, a subject of the German Emperor, and resident of Aachen, Germany, have invented 5 certain new and useful Improvements in Processes for the Manufacture of Nitric Acid or Nitrates from Nitrogen Oxids, of which the following is a specification.

In hitherto known processes for the manufacture of nitric acid by direct conversion of nitrogen oxids (NO, NO₂, N₂O₃, N₂O₄) which can be obtained by the action of electric discharges on a mixture of nitrogen and oxygen, and which contain less than 15 74% of oxygen which is the oxygen content of nitrogen pentoxid (N₂O₅) there is produced, in addition to nitric acid, also nitrous acid, or in addition to nitrate, also nitrite, according as the gases are conveyed into an 20 aqueous or an alkaline liquid.

The process is represented by the following equations:—

30 The present process relates to the conversion of nitrogen oxids, whether they be obtained by the action of suitable voltaic arcs or by oxidation of ammonia, or in some other way, into a pure nitric acid or nitrate. The said conversion can be obtained according to this invention by carrying out the further oxidation of nitrogen oxids in the presence of suitable catalysts. As catalysts there may be used for instance metallic cobalt and nickel, as well as the various oxid compounds of the said metals, preferably their nitrates.

45 The catalysts (or catalysts) are preferably used on suitable supports such as asbestos-wool, asbestos-cardboard, magnesia, clay, etc. If it is desired to use oxids, it is advisable to impregnate the supports with solutions of the corresponding nitrate, and then 50 to calcine with admission of air. The nitrates are placed on the supports preferably in an aqueous or alcoholic solution, the drying being carried out at 100-120°. The process is for instance carried out by passing 55 a mixture of nitrogen oxids with a gaseous

oxidizing agent such as oxygen or suitable oxygen-containing gas mixtures, through a tube filled with the contact mass, in which takes place the further oxidation of the nitrogen oxids. The process is preferably carried out for instance by passing nitrogen oxids of any desired origin, mixed with oxygen which has been rendered active for instance by passing it through a Siemens's ozone battery, through a tube charged with suitable contacts, for instance nickel nitrate contacts. The quantity of oxygen must be of course calculated so that it is sufficient for complete oxidation of the nitrogen oxids to (theoretically) N₂O₅. The gas escaping from the contact tube, is collected in the well-known manner either in water or in an alkaline aqueous liquid. In the former case a pure nitric acid is obtained, in the second a pure nitrate. 75

When working in accordance with the foregoing example, the catalytic oxidation takes place at an ordinary temperature. For the rest, it is simply question of finding by experiments for each separate case, which 80 are the best temperatures for the contacts used.

I claim:—

1. A process of making nitrates which comprises bringing a gaseous oxidizing agent and nitrogen oxids containing less than 74% of oxygen into contact with an oxidizing catalyst and contacting the nitrogen pentoxid in the resulting gas mixture with an alkaline aqueous liquid. 90

2. A process of making nitric acid anhydrid which comprises bringing a gaseous oxidizing agent and nitrogen oxids containing less than 74% of oxygen into contact with an oxidizing catalyst. 95

3. A process of making nitric acid anhydrid which comprises bringing a mixture comprising oxygen and nitrogen oxids containing less than 74% of oxygen into contact with an oxidizing catalyst. 100

4. A process of making nitric acid anhydrid which comprises bringing a mixture comprising oxygen, ozone and nitrogen oxids containing less than 74% of oxygen into contact with an oxidizing catalyst. 105

5. A process of making nitric acid anhydrid which comprises bringing a mixture comprising oxygen and nitrogen oxids containing less than 74% of oxygen into contact with an oxidizing catalyst containing nickel. 110

6. A process of making nitric acid anhydrid which comprises bringing a mixture comprising oxygen and nitrogen oxids containing less than 74% of oxygen into contact with a catalytic nickel-oxygen compound.
7. A process of making nitric acid anhydrid which comprises bringing a mixture comprising oxygen and nitrogen oxids containing less than 74% of oxygen into contact with nickel nitrate.
8. A process of making nitric acid anhydrid which comprises bringing a mixture comprising oxygen, ozone and nitrogen oxids containing less than 74% of oxygen into contact with an oxidizing catalyst containing nickel.
9. A process of making nitric acid anhydrid which comprises bringing a mixture comprising oxygen, ozone and nitrogen oxids containing less than 74% of oxygen into contact with a catalytic nickel-oxygen compound.
10. A process of making nitric acid anhydrid which comprises bringing a mixture comprising oxygen, ozone and nitrogen oxids containing less than 74% of oxygen into contact with nickel nitrate.

In testimony whereof I have signed my name to this specification in the presence of two subscribing witnesses.

ALEXANDER CLASSEN.
